PROPHYLACTIC COMPOSITION FOR SCOURS

Karl Paul Link, Middleton, Wis., assignor to Wisconsin Alumni Research Foundation, Madison, Wis., a corporation of Wisconsin

No Drawing. Application August 2, 1949,
Serial No. 108,233

5 Claims. (Cl. 167—53)

1

The present invention relates to a new composition of matter, and more specifically to a composition having particular utility in the prophylaxis of scours.

Scours is a disease of the new-born that suck, i. e. Mammalia. It can be fatal. Indeed it is held that it is one of the commonest causes of death of young farm animals. According to Spielman, A. A., in the article, "Do calves need vitamin supplements?" Feedstuffs, vol. 18, No. 1 (1946), the mortality of calves on many dairy farms in the United States during the first week or weeks of life primarily ascribed to scours is estimated at 15-20 per cent. Also, according to the U. S. D. A. Yearbook, Keeping Live Stock Healthy, U. S. Gov. Printing Office (1942), 20-40 per cent of lambs may die in severe outbreaks of dysentery sometimes called "white scours," whilst 50 per cent of new-born pigs may die of enteritis (or three day pig disease) and scours. The chief symptoms preceding death are diarrhea (hence the name scours), inflammation of the umbilical stump, and a general exudative arthritis.

The primary cause of scours is strains of bacteria of the colon group (*Bacillus coli* or *coli aerogenes*) encountered by the new-born for the first time and against whom a resistance must be developed for survival. Colon group bacteria of this type are non-pathogenic under normal conditions, *B. coli* being the first organism to establish itself in the large intestine after birth. So long as it is confined to the intestine it lives as a saprophyte, but if the integrity of the alimentary mucous membrane is impaired in any way, it may invade the tissues. Smith, T. and Little, R. B., Jour. Exp. Med. 30, 181 (1922); Gaiger and Davies, Veterinary Pathology and Bacteriology, 3rd ed. (1947). Associated factors that predispose or aggravate the disease are contaminated or infected quarters, improper feeding of the mother or young, and exposure to cold and dampness. Specific preventatives are clean quarters, proper feeding and particularly of the new-born with the first milk (colostrum), freedom from cold and dampness, and where infection is present the isolation of infected animals. In highly virulent epizootics of scours, however, all or nearly all of the young may become infected and survival varies depending on the degree of resistance and vigor that has been developed shortly after birth. This is particularly the situation with the calf, lamb and pig which unlike the ape and man, get little or no immune bodies by intrauterine or placental transmission.

2

sion. It is also applicable to rabbits and the like which fall between man and the ruminant of the calf type.

5 The new-born mammal is for all practical purposes born in a state of physiologic shock. Hemorrhagic petechiae are present in the intestinal tract which is essentially a delicate "raw" membrane. Within 7-10 days, a very noticeable morphological change sets in and the hemorrhagic petechiae largely disappear from the tract. Adjustment must be made from a wet (physiologically balanced) to a dry, unbalanced environment. Adjustment must also be made to two new conditions (a) fluid balance
10 and (b) nourishment by mouth as opposed to nourishment via the placenta. Imposed on these is the urgent necessity of developing resistance to the new bacterial flora encountered.
15 The change may be stated as:

20	Aseptic environment (In the uterus)	→	Septic environment (Outside the uterus)
	Immunity via the mother		Immunity must be developed

25 The problem presented by scours has been recognized for many years and many specific preventative measures and recipes for treatment, particularly for calf scours have been proposed.

The preventive measures for calf scours include assurance that the calf receives an ample supply of colostrum, isolation of mother and calf to clean quarters, use of a muzzle to prevent the calf from eating contaminated litter and over-eating, injection of antibacterial serum-bovine, the feeding of milk diluted with lime water, feeding acidophilus milk, administration of vitamin A and certain members of the B complex and use of sulfa drugs. Udall, D. H., The Practice of Veterinary Medicine, Utica, N. Y., 5th ed.,

40 1947. The feeding of milk diluted with water has also been proposed, Sheehy, E. J., The Scientific Proceedings of the Royal Dublin Society, 21, (N. S.) No. 9, 73 (1934).

45 The treatment of choice for the prophylaxis of
scours is an ample supply of bovine colostrum
(the first milk) since it has been demonstrated
that it contains in addition to the essential food
elements, immune proteins or antibodies which
50 pass through the "raw" digestive tract to the
blood stream during the first days after birth
and passively immunize the new-born. Smith, T.
and Little, R. B., *Jour. Exp. Med.* 30, 181 (1922);
Smith, E. L., and Holm, A., *Jour. Biol. Chem.*
55 175, 349 (1948).

The use of colostrum while recognized to be highly effective when good quality colostrum is available is frequently impractical since colostrum with a sufficient antibody or immune protein content is not always available in adequate amounts. Furthermore, there appears to be a marked difference in the immunizing capacity of the colostrum of different bovine breeds resulting in a greater susceptibility to scours in the new born of some breeds, Wise, G. H., and Anderson, G. W., *Jour. Dairy Science*, 27, 965 (1944).

The use of calf scour serum (antibacterial serum-bovine) Smith, T., *Jour. Exp. Med.* 51, 473; 483; 519 (1930) has also been employed as a prophylactic (and cure). This proposal though scientifically sound has not been widely adopted in all probability because the serum needs to be injected intravenously and this requires the services of skilled personnel such as a veterinarian.

In place of commercially prepared serum, the use of the dam's blood (defibrinated and citrated) has also been proposed, the administration being intravenous or subcutaneous. This practice has not met wide adoption, even though recognized to be effective, since it requires the use of skilled technicians, see Udall, *supra*.

Next to colostrum, the sulfa drugs are probably the most widely used for the prevention of calf scours. The use of the sulfa drugs, however, is not without risk due to their toxic effects. Wise and Anderson, *supra*. The other preventive measures listed above have been used to a limited extent but each has its shortcomings. Udall, *supra*.

The art has long desired an effective, non-toxic, commercially practical prophylactic for scours that can be given orally. In particular, the art has desired a relatively inexpensive composition readily adaptable for use on farms, ranches and the like that does not require for administration the services of medically skilled personnel.

The principal object of the present invention is to provide an effective, non-toxic composition for preventing or inhibiting scours in calves, lambs, goats, pigs, rabbits and the like.

Another object of the present invention is to provide an effective composition for preventing scours that can be given orally.

A further object of the present invention is to provide an inexpensive, commercially practical composition for preventing scours that is readily adaptable for administration by personnel available on farms, ranches and the like.

Other objects of the present invention will be apparent as the detailed description proceeds hereinafter.

I have discovered a combination of commercially available ingredients that actively cooperate to produce an effective composition for preventing or inhibiting scours. The composition which is administered per os contains as essential ingredients immune bodies from blood, together with a small but effective amount of vitamin K or a compound characterized by vitamin K anti-hemorrhagic activity. This combination may be used with a Ringer-Tyrode salt mixture, or with suitable food for the new-born animal such as colostrum, milk solids and the like, and for oral feeding can be incorporated into water or in water containing the Ringer-Tyrode physiological salt mixture.

Immune bodies.—The immune proteins or antibodies used in the present invention are ob-

tained from mammalian blood and preferably from non-citratized pooled blood of dairy cattle or blood from sheep, pigs, etc. The blood may be secured by the bleeding of the animals including animals which have been specially treated to provide hyper-immune blood, although a readily available and satisfactory source of blood is that available in the processing of animals at an abattoir. The immune proteins carried in plasma, serum, Howes Na₂SO₄ globulin fraction or the like, may be produced from the blood by processing the blood in accordance with standard practices in the art. The desired plasma, serum or globulin fraction may be spray dried or be subjected to freeze-drying. Satisfactory procedures are described in the Medical Research Council Report No. 258, *The Preservation of Proteins by Drying*, by R. I. N. Greaves, H. M. S. Stationary Office (1946).

Vitamin K.—The vitamin K or vitamin K compound used in the present invention may be natural vitamin K, such as K₁ or K₂, or various natural or synthetic compounds which promote the formation or activation of prothrombin. Some of the effective compounds are 2-methyl-1,4-naphthoquinone (Menadione); 2-methyl-1,4-naphthoquinone-3-sodium sulfonate ("Hykinone"); 4 - amino - 2 - methyl - 1 - naphtholhydrochloride ("Synkamin"); 2-methyl-3-hydroxy-1,4-naphthoquinone (Phthiocol); 2-methyl - 1,4 - naphthoquinone - diphosphoric acid ester tetrasodium salt ("Synkavite"); 2-methyl-1,4 naphthoquinone; 2-methyl-1,4-naphthoquinone diacetate and 2 - methyl - 1,4 - dihydroxy - 3 - naphthaldehyde. When a water insoluble vitamin K composition such as natural K₁ or K₂ is employed, the addition of bile salts to facilitate absorption is recommended.

The following examples will serve to illustrate the invention.

Examples

		Grams
A.	Bovine plasma	2500
	Menadione (2-methyl - 1,4 - naphthoquinone or its equivalent)	1-2
B.	Bovine plasma	2500
	Menadione (2-methyl - 1,4 - naphthoquinone or its equivalent)	1-2
	Ringer Tyrode salts ¹	9.65
C.	Partially digested milk solids	7500
	Bovine plasma	2500
	Menadione (2-methyl - 1,4 - naphthoquinone or its equivalent)	1-2
	Ringer Tyrode salts ¹	9.65

¹ NaCl, 8.00 grams; KCl, 0.20 gram; CaCl₂, 0.20 gram; NaHCO₃, 0.10 gram; NaHPO₄, 0.05 gram; MgCl₂, 0.10 gram; glucose, 1.0 gram.

The plasma is prepared from pooled dairy cow blood in accordance with standard practices in the art, and then spray dried or freeze dried. The vitamin K (commercially available under the name "Menadione") is a crystalline solid. The partially (or enzyme) digested milk solids are prepared by treating cows milk with pancreatin for about one hour at 40° C., the digested mixture pasteurized at 75° for thirty minutes, and then spray dried.

In each example the ingredients are intimately mixed in the dry state, and then stored in a suitable stoppered container in which form the mixtures are stable when kept refrigerated.

When ready for administration sufficient water is added for every 50 grams of plasma to provide one liter of composition. It is ordinarily preferred to administer the composition from a drench bottle or it can be fed from a pail. In practice it is preferred to offer an equal volume of water immediately after administration—or the composition containing 50 grams of plasma with or without the digested milk solids and with or without the Ringer-Tyrode salt mixture, can be made up to 2 liters directly and administered in that dilution.

For a calf two feedings of a composition containing 50 grams of plasma in one or two liter volumes each per day for two to four days is generally satisfactory. For smaller animals such as the rabbit, oral administration (via a wide tipped dropper) of about 2-4 cc. of the composition of Example C (from a suspension containing 200 grams per liter) daily increasing up to about 10-12 cc. by the seventh day has proven satisfactory. For example, in a colony of rabbits particularly susceptible to scours (mucoid enteritis) where the survival was approximately 52%, the administration of the composition of Example C of the present invention increased the survival to about 85%.

The proportions of ingredients employed above are merely illustrative, and they may be varied to meet particular needs. When using plasma and milk solids it is ordinarily preferred to use at least about one part of partially digested milk solids to one part of plasma, and in most instances it is preferred to use compositions containing a major proportion (60-90 per cent) of milk solids and a minor proportion (10-40 per cent) of plasma. The three to one ratio (75 per cent milk solids to 25 per cent plasma) employed in Example C has been found to give excellent results in practice. The amount of vitamin K compound used may also be varied within wide limits depending, for example, upon the activity or anti-hemorrhagic characteristics of the vitamin K compound selected, etc. Preferably the vitamin K compound is used in excess and in all cases is present in sufficient amounts to substantially reduce the extent and duration of hypoprothrombinemia (a condition found in new-born) and the persistence of the hemorrhagic petechiae in the intestinal tract. A composition providing a daily dosage of around 40 to 80 mg. of Menadione is indicated for relatively large animals.

Investigations have demonstrated that the immune proteins (antibodies) used in the present invention when absorbed unaltered from the alimentary canal and into the blood in active condition passively immunize new-born animals against *B. coli* and related organisms causing scours. See Smith, T. and Little, R. B., Jour. Exp. Med. 30, 181, (1922); Smith, E. and Holm, A., Jour. Biol. Chem. 175, 349 (1948). Investigations have also demonstrated that such immune bodies are readily absorbed unaltered and in active condition from the digestive tract of new-born up to about 7 to 10 days after birth when administered with vitamin K.

The vitamin K used in the composition of the present invention reduces the extent and duration of hypoprothrombinemia and the persistence of hemorrhagic petechiae, i. e. minute hemorrhages in the digestive tract. The action on the digestive tract is of utmost importance as it blocks portals for entry of scour producing organisms into the blood stream. Also, at the same time the administration of vitamin K changes the normally hemorrhagic condition of the digestive tract of the new-born to a nonhemorrhagic condition more suitable for rapid absorption of the immune bodies into the blood. The operation of the basic (immune body-vitamin K) ingredients of the present invention thus involves cooperative action of the type long desired for preventing scours.

It will be understood that the present invention is not limited to the above illustrative examples and that the use of equivalent materials fall within the scope of the invention. Examples are the use of serum (defibrinated blood) and immune fractions such as Howe's Na_2SO_4 globulin fraction and the like, in place of the plasma described above. It will also be understood that the composition of the present invention may be used to combat scours in various animals including the rabbit, pig, goat and lamb as well as the calf.

I claim:

1. A non-toxic composition for oral administration having utility in the prophylaxis of scours, comprising as essential ingredients immune proteins derived from mammalian blood and a vitamin K compound.
2. A non-toxic composition for oral administration having utility in the prophylaxis of scours, comprising bovine plasma containing immune proteins derived from the blood of dairy cattle and a vitamin K compound.
3. A non-toxic composition for oral administration having utility in the prophylaxis of scours, comprising bovine serum containing immune proteins derived from the blood of dairy cattle and a vitamin K compound.
4. A non-toxic composition for oral administration having utility in the prophylaxis of scours, comprising as essential ingredients immune proteins derived from the blood of cattle and a vitamin K compound.
5. A non-toxic composition for oral administration having utility in the prophylaxis of scours, comprising bovine plasma containing immune proteins derived from the blood of cattle and menadione in a ratio of 1-2 grams per 2500 grams of plasma.

KARL PAUL LINK.
